UNITED STATES PATENT OFFICE.

WELLINGTON RANDALL, OF MARYSVILLE, WASHINGTON.

RAIL-TIE.

1,099,616.

Specification of Letters Patent.

Patented June 9, 1914.

Application filed March 16, 1914. Serial No. 825,093.

To all whom it may concern:

Be it known that I, WELLINGTON RANDALL, a citizen of the United States, residing at Marysville, in the county of Snohomish and 5 State of Washington, have invented certain new and useful Improvements in Rail-Ties; and I do hereby declare the following to be a full, clear, and exact description of the invention, such as will enable others skilled 10 in the art to which it appertains to make and use the same.

My invention relates to new and useful improvements in rail ties and more particularly to an attachment for wooden, concrete or other ties which will enable the securing of the rails in a reliable manner without necessitating employment of spikes, bolts or other fastening means.

Another important object of my invention 20 is to provide a rail tie of the character described which is constructed to provide desired resilient action, will prevent spreading and creeping of the rails and which is constructed to enable an expeditious and reliable securing of the rails relative thereto.

Another important object of my invention is to provide a rail tie of the character described which is simple as to construction, reliable and efficient in operation and cheap 30 to manufacture.

The above and additional objects are accomplished by such means as are illustrated in the accompanying drawings, described in the following specification and then more 35 particularly pointed out as claimed.

With reference to the drawings, wherein I have illustrated the preferred embodiment of my invention as it is reduced to practice, and throughout the several views of which 40 similar reference numerals designate corresponding parts, Figure 1 is a side elevation of my improved tie showing the rails in section and secured thereto, Fig. 2 is a fragmentary top plan view showing my improved tie and a rail secured thereto, and Fig. 3 is a longitudinal sectional view partly in elevation showing a portion of the tie and the cushioning strip used when the plate to be attached to the tie is used in connection 45 with a concrete, steel or other tie other than the usual wooden ones.

Referring to the drawings, the numeral 1 designates as an entirety a tie having secured thereon upon the upper face thereof a 50 rectangular preferably metallic plate 2. The

plate 2 is of the same length and width as the tie so as to have its edges disposed flush with the edges of the tie.

As a means for securing the plate 2 I provide upon each end of the plate on the 60 opposite sides thereon spaced apertured lugs 3 which extend outwardly from the plate and receive bolts 4 which have suitable nuts 5 turned on their unheaded terminals. A metallic band or strap 6 is secured in any 65 suitable manner at its ends to the bolts 4 to that portion of the bolts between the lugs 3 and is passed around the sides and bottom of the tie 1. These bands or straps 6 serve to securely hold the plate 2 upon the tie 1. 70

As a means for clamping the rails A I provide upon the plates adjacent each end thereof an upwardly struck integral rail clamping flange 7. The flanges 7 coöperate with rail clamping members 8 that are 75 detachably secured to the plate 2 by means of bolts 9 having nuts 10 turned on their upper unheaded terminals.

As shown in Fig. 3 the tie 1 is formed of metal and to provide the desired resiliency 80 given by the wooden ties I position upon the tops of the tie 1 a wooden strip or plate 11 of the same size as the plate 2 preferably. I then place the plate 2 upon the wooden strip or plate 11 and secure the plate 2 in 85 the manner such as described. The wooden strip 11 provides the desired resilient action. This wooden strip 11 is used in connection with the plate 2 when the plate 2 is to be attached to ties formed of material other than 90 wood such as concrete and metal ties.

It will be readily seen that my device may be attached in an expeditious and reliable manner to the ordinary style of cross ties without necessitating any change in the construction of the cross tie or requiring much 95 time or labor.

In practice, I have found that the form of my invention, illustrated in the drawings and referred to in the above description, as 100 the preferred embodiment, is the most efficient and practical; yet realizing that the conditions concurrent with the adoption of my device will necessarily vary, I desire to emphasize the fact that various minor 105 changes in details of construction, proportion and arrangement of parts may be resorted to, when required, without sacrificing any of the advantages of my invention, as set forth.

What is claimed is:—

1. A rail tie comprising an elongated plate adapted to be secured upon the upper face of wooden, concrete or other ties, rail clamping means carried adjacent the ends of the plate, spaced apertured lugs formed in pairs adjacent the ends of the plate upon opposite sides thereof, bolts inserted through said lugs and a securing band secured at its ends 10 to said bolts and extending around and under said tie.
2. In a device of the character described, the combination with a rail tie of a plate mounted upon said rail tie and having its 15 edges disposed flush with the edges of said rail tie, integral clamping flanges on said

plate, removable clamping members coöperating with said clamping flanges mounted on said plate, spaced apertured lugs formed integral with said plates adjacent the ends 20 thereof and upon opposite sides of said plate, bolts inserted through said flanges and securing bands operatively connected with said bolts and extending beneath said tie and in engagement with the side and bottom 25 thereof.

In testimony whereof I affix my signature in presence of two witnesses.

WELLINGTON RANDALL.
